CANE CAR

Kaare O. Asper, Honolulu, Territory of Hawaii,
assignor to Pressed Steel Car Company, Inc.,
Pittsburgh, Pa., a corporation of Pennsylvania

Application July 22, 1939, Serial No. 285,930

6 Claims. (Cl. 105—238)

My invention pertains to cane cars and in particular to metal end posts for same.

An object of my invention is to provide an end post which is rigid and cooperates with the wooden car underframe to strengthen the car.

Another object of my invention is to provide an end post having means for embracing the end and adjacent longitudinal sills to retain same in rigid relationship.

10 A further object of my invention is to provide an end post of the character described which slopes upwardly and outwardly from the end sill to provide increased capacity to the car.

Referring now to the drawings forming part of this specification wherein like reference characters refer to like parts: Fig. 1 shows in side elevation a car equipped with end posts forming the invention; Figs. 2 and 3 show alternate arrangements of the end posts with the end and longitudinal sills of the car; Fig. 4 shows an end elevation of the post assembled with the end sill and bottom plate; Fig. 5 shows in side elevation the post of Fig. 4 assembled with the end and longitudinal sill; Fig. 6 shows in plan the post of Figs. 4 and 5; Fig. 7 shows a plan view of the bottom plate; Fig. 8 shows in enlarged detail a plan view of the post of Fig. 2 assembled with a single longitudinal member; Fig. 9 shows in enlarged detail a plan view of the post of Fig. 3 assembled with two longitudinal members.

Referring now in detail to the drawings, reference character 1 indicates the car end sills, which are two in number, disposed at opposite ends of the car and connected by longitudinally disposed side sills 2. Intermediate the side sills and connecting the end sills are bearing sills 3. These end, side, and bearing sills are preferably of wood although they may be of any other suitable materials and for a purpose hereinafter set forth are preferably of the same depth. As in the usual wood car construction the sills 2 and 3 may be mortised into the end sills 1. Secured to the end sills and extending upwardly therefrom are end posts 4. These end posts are usually arranged two or more at each end of the car and secured to the end and longitudinal sills, as illustrated in Fig. 2 or 3 of the drawings. The posts at opposite ends of the car are preferably connected by longitudinally disposed members such as chains, having depending chain members secured thereto and to the side sills or floor of the car. Whilst no floor construction has been shown for the car, the usual floor construction common to this type of car may be used. The end walls of the car, which are illustrated in

Fig. 1 of the drawings, preferably comprise wood planks mounted on the end posts and extending therebetween.

Referring now to Figs. 4 to 7, inclusive, of the drawings each end post comprises a base formed of angularly disposed portions 8 and 9, and an integral upwardly extending web portion 10. The base portion 8 overlies the top face of the end sill 1 and extends inwardly therefrom along the top face of the adjacent longitudinal sills 2 or 3, as illustrated in Figs. 8 and 9 of the drawings. The base portion 8, angularly disposed to the base portion 9, overlies the outer face of the end sill 1 and preferably terminates above the bottom edge thereof. As illustrated in Fig. 5 of the drawings, the base portions 8 and 9 of the post embrace adjacent angularly disposed faces of the end sill 1. Disposed beneath the end sill 1 and below the base portion 8 of the post is a bottom tie plate 14, the base portion 8 of the post and the tie plate being connected by suitable bolts, as illustrated in Figs. 8 and 9 of the drawings. In these latter figures it will be observed that the bolts 15 pass through the end sill 1 and the bolts 18 and 21 substantially embrace the adjacent longitudinal sill. By reason of the portion 9 of the base of the post terminating above the lower plane of the end, side, and bearing sills the bolts 15, 17, and 18 may be tightened so as to grip these sills between the base of the post and the plate 14, thereby retaining the car underframe and post in rigid relation and preventing weaving of the car.

In Figs. 2 and 8 of the drawings the bolts 18 lie on opposite sides of the bearing sill 3 and connect the base portion 8 with the bottom tie plate 14. In Figs. 3 and 9 of the drawings the bolts 18 are omitted and bolts 21, lying adjacent the spaced bearing and side sills 2 and 3, secure the bottom portion 8 of the post to the tie plate 14. In this latter arrangement it is preferable to use a small spacing block 22 between the sills 2 and 3, as illustrated in Fig. 9 of the drawings. The vertically disposed base portion 9, adjacent its lower edge thereof, has lugs 16 extending outwardly therefrom and provided with suitable apertures through which bolts 17 are placed connecting the lugs 16 with the tie plate 14. This base portion 9 of the post may have suitable apertures, such as 23, through which lag screws or other means may be inserted to secure the base portion 9 to the adjacent face of the end sill 1.

The web portion 10 of the post extends upwardly from the base thereof and preferably has one edge constituted as a flange 11 forming a

55

continuation of the base portion 9 of the post. The opposite edge of the web 10 is formed by flange 12 which extends upwardly at an obtuse angle from base portion 8 for a short distance 5 then continues upwardly at a greater angle to the top of the post 4. Thus the web 10 is wider at the bottom than at the top. The web 10 extends to adjacent the free edge of base portion 8 of the post and thus overlies the adjacent longitudinal sill in Figs. 2 and 8 of the drawings. This abrupt widening of web 10 adjacent the base thereof greatly increases the strength of the post. The web 10 has in line therewith a rib 13 extending along the flange 11 and base portion 9 to 15 further strengthen the post at the juncture between the web 10 and base of the post.

The flange 12 of web 10 has suitable apertures therein for reception of bolts to secure the wooden end wall planks 7 to the posts and web 10 may 20 have suitable apertures therein as at 24 for passage of brake levers in case the car is equipped with suitable brakes.

The particular contours of base portion 8 and flanges 11 and 12 may vary according to design 25 requirements without departing from the spirit of the invention and I do not wish to limit myself to the particular details shown except as made necessary by the scope of the appended claims.

30 Having thus described the invention what I claim as new and desire to secure by Letters Patent is:

1. In a car underframe structure including wooden end and longitudinal sills, a combination 35 sill bracket and post structure comprising an inverted L-shaped base overlapping the outer face of the end sill and the top faces of the end sill and adjacent end of the longitudinal sill, apertured means defining the lower edge of the 40 L-shaped base at the outer face of the end sill and terminating above the bottom face of the end sill, a base plate disposed beneath the said end and longitudinal sills and beneath said L-shaped base, and bolts connecting the said L-shaped base and base plate at said apertured 45 means and at said longitudinal sill, the bolts at said longitudinal sill being disposed at opposite sides thereof.

2. In a car underframe structure, in combination 50 with a wooden end sill and abutting longitudinal sill, a metal post base of inverted L-shape having the vertical leg thereof engaging the outer face of the end sill and the horizontal leg engaging the top face of the end and of the longitudinal 55 sills, a base plate beneath the post base and engaging the bottom faces of the end and the longitudinal sills, bolts disposed at opposite sides of the longitudinal sill in spaced relation to the end sill and connecting the post base and base 60 plate, outstanding lugs on the vertical leg of the post base in spaced relation to the base plate and bolts connecting the post base lugs and base plate in spaced relation to the end sill.

3. In a car of the character described having an underframe including wooden end and connecting longitudinal sills, an end post comprising an inverted L-shaped base, an upwardly extending body portion united with the base and a 5 bottom plate for connection with said base, the vertical leg of said L-shaped base engaging the outer face of the end sill and terminating in outstanding flange portions disposed above the bottom face of the end sill, the horizontal leg of 10 said L-shaped base engaging the top face of the end sill and the top face of the adjacent end of one of said longitudinal sills, the bottom plate engaging the bottom faces of the said end and longitudinal sills, and bolts connecting the post 15 base and bottom plate at the longitudinal sill and exteriorly of the outer face of the end sill to clamp said sills between the post base and the bottom plate.

4. In a car underframe structure, in combination 20 with an end sill, a pair of spaced longitudinal sills abutting the end sill, a vertically disposed post at the end sill, a base on said post secured to the end sill and having a vertically depending portion engaging the outer face of the end sill 25 and a horizontally disposed portion engaging the top faces of the end sill and of both abutting longitudinal sills, apertured lugs on said vertically depending post base portion extending outwardly therefrom and in spaced relation to the 30 bottom face of the end sill, a base plate engaging the bottom faces of the end sill and the adjacent longitudinal sills and extending beneath the post base and projecting lugs, apertures in said plate, and bolts connecting said post base and base plate 35 at said lugs and between said longitudinal members adjacent the ends of the base plate.

5. In a car underframe structure, a wooden end sill, an abutting longitudinal sill, a post secured to the end sill and having an inverted L-shaped 40 base engaging the outer face of the end sill and the top faces of the end and longitudinal sills, a base plate disposed beneath said post base and the bottom faces of the end and longitudinal sills, bolts connecting the post base and base 45 plate independently of said sills and on opposite sides of the end sill.

6. In a car underframe structure, a wooden end sill, an abutting longitudinal sill, a post secured to the end sill and having an inverted L-shaped 50 base engaging the outer face of the end sill and the top faces of the end and longitudinal sills, a base plate disposed beneath said post base and the bottom faces of the end and longitudinal sills, bolts connecting the post base and base 55 plate independently of said sills and on opposite sides of the end sill, and an upwardly extending post body portion secured to the post base and having one face thereof inclined upwardly and outwardly from the top face of the longitudinal 60 sill.

KAARE O. ASPER.
